FIG. 5

FIG. 6

Technical drawings illustrating a mechanical assembly, likely a conveyor or transport system. The drawings show a top-down view and a side view.

FIG. 5 (Top-Down View): This view shows a rectangular frame with various components. Key parts include:

- Left side: A vertical wall with circular features labeled 50, 52, 55, 57, 59, 60, and 62.
- Center: A horizontal conveyor belt supported by a series of rollers. Labels include 30, 55, 61, 100, 21, 300, 81, 82, 84, 85, 90, 100, 110, and 300.
- Right side: A vertical wall with a door or panel labeled 99.

FIG. 6 (Side View): This view shows the assembly from the side, revealing internal components and structural details. Key parts include:

- Top: A horizontal beam with a central slot and supports labeled 65, 68, 71, 80, 81, and 99.
- Middle: A vertical wall with a door or panel labeled 99.
- Bottom: A base structure with a door or panel labeled 110.
- Left side: A vertical wall with circular features labeled 50, 52, 55, 57, 59, 60, and 62.
- Right side: A vertical wall with a door or panel labeled 99.

UNITED STATES PATENT OFFICE.

LIONEL COKE HILL, OF MONTREAL, QUEBEC, CANADA.

CAR DUMPER.

Application filed July 1, 1921. Serial No. 481,739.

To all whom it may concern:

Be it known that I, LIONEL COKE HILL, a subject of His Majesty, King George Fifth, of Great Britain, residing at Mont-
real, in the Province of Quebec, Dominion
of Canada, have invented a new and useful
Improvement in Car Dumpers, of which the
following is a specification.

This invention relates to improvements in
car dumpers and is fully described and ex-
plained in this specification and shown in
the accompanying drawings.

I have here shown the features of my in-
vention embodied in a device for dumping
railroad side-door box cars loaded with grain
or similar material. It is obvious, however,
that, without detracting from the spirit of
my invention, the features thereof may be
embodied in devices adapted for dumping
other kinds of cars loaded with other ma-
terials.

In the accompanying drawings, Figure 1
is a view in side elevation of a car dumper
embodying the features of my invention,
Figure 2 is a top plan view of the same,
Figure 3 is a view taken as indicated by the
line 3 of Fig. 1, Figure 4 is a fragmentary
view in end elevation showing some of the
parts in altered position, Figure 5 is a dia-
grammatic view similar to Fig. 1 showing
some of the parts in altered positions, Fig-
ure 6 is a diagrammatic view similar to Fig.
3, showing some of the parts in altered po-
sitions, Figure 7 is a detailed view of a part
of the car-door opener, Figure 8 is a view
similar to Fig. 7 showing some of the parts
in altered positions, Figure 9 is a view taken
as indicated by the line 9 of Fig. 8, and Fig-
ure 10 is a view taken as indicated by the
line 10 of Fig. 3.

In general, it may be stated that the de-
vice comprises an elevator track section nor-
mally lying in alignment with fixed receiv-
ing tracks and fixed discharge tracks, upon
which the car to be unloaded is run. Stops
or other means are provided for centering
or spotting the car on the elevator track
section. Means are provided for elevating
the track section and tilting the same side-
ways, so that grain in the car will run out
of the side door into a suitable receiving bin.
It is obvious, however, that such sideways
tilting will not empty the car, since some

grain will remain in the ends. In order to
empty the ends, therefore, means are pro-
vided for also tilting the car longitudinally.
After the car has been tilted sideways first
one end is raised, and then the other, in
order to cause the grain in the ends to flow
down toward the door and out through
the same. It is usually found necessary to
raise one end of the car, then the other, and
then again the first end by a rocking or
back-and-forth movement in order to com-
pletely empty the same; although it is obvi-
ous that this longitudinal rocking or alter-
nate raising of the ends may be repeated as
often as desired, or as often as necessary in
order to empty the car completely. Means
are also provided for automatically remov-
ing the boards which usually seal the inside
of the car-door opening.

I will now describe the device more in de-
tail. 20 indicates two longitudinally-ar-
ranged parallel I-beams on which are mount-
ed track rails 21 normally lying in aline-
ment with fixed receiving track rails 22 and
fixed discharge track rails 23. The beams
20 are normally supported at their ends on
abutments 24 and further supported at two
places between the ends by the walls 25.
The beams 20 are joined together by a pair
of transverse channel irons 26 near each end
lying beneath the same. The ends of the
channel irons 26 project some distance be-
yond the members 20 on each side, as shown
in Fig. 3, said projecting ends being longer
at one side than the other. The beams 20
with the track rails 21 mounted upon them,
and joined by the transverse channel irons 26,
form a rigid structure which may be
referred to as an elevator platform, although
it is to be noted that there is not necessarily
flooring or similar flat surface. Below this
platform is provided a suitable pit or other
excavation so that when the platform is in
its lowest or normal position, the rails 21
on the platform will be level with the fixed
receiving and discharge rails, 22 and 23, at
the ends of the excavation.

The following means are provided for ele-
vating the platform with the rails 21. At
each side of the platform are two vertical
posts 30 carrying on their upper ends cross-
members 31 which in turn support longitu-
dinal members 32 upon which is mounted

suitable hoisting apparatus for elevating the platform. The cross-members 31 are supported by suitable trusses and framing 35; and likewise, the two outer longitudinal members 32 are supported by suitable trusses and framing, indicated in general by 36, in order to give rigidity and strength to the entire structure. I will now describe in detail the hoisting mechanism. Supported in 10 suitable bearings mounted on the members 32 is a transversely-arranged shaft 40 having mounted on its ends the drums 41 and 42, the former being slightly larger than the latter. The shaft 40 also has mounted on it a gear wheel 43 meshing with and adapted to be driven by a pinion 44 arranged above it on the shaft 45 which in turn is provided with a gear wheel 46. A motor 47 is provided, connected by a belt 48 to a wheel 20 mounted on a shaft 49 which has a worm 50 on its end meshing with and adapted to drive the gear wheel 46. The motor 47 is reversible, and any suitable means, such as a clutch, as indicated in general by 52, are provided with a belt 48. By means of this construction the drums 41 and 42 may be given rotation in either direction by the motor, and the worm 50 makes the action irreversible. A cable 55 is provided with both 30 ends attached to the drum 42. From this drum, the cable 55 is laid over the pulley 57, thence downwardly and around the sheave 58, thence upwardly over the drum 59, around which it makes two or three turns, 35 thence over the top of the structure to the other end where it passes over the pulley 60 from which it is led downwardly around the sheave 61, thence upwardly over the pulley 62 and back to the drum 42. Similarly, a 40 cable 65 has its ends fastened to the larger drum 41 on the other side of the structure. From this drum, the cable 65 is led over a pulley 67, thence downwardly around the sheave 68, thence upwardly over the drum 69, around which it is wound two or three 45 times, thence above the structure to the other end and over the pulley 70, thence downwardly around a sheave 71 similar to the sheave 61 and located opposite thereto, 50 thence upwardly over the pulley 72 and back to the drum 41. The sheave 58 is attached to the longer projecting ends of the channel irons 26, at one end of the platform, and likewise the sheave 61 is attached at the 55 other end of the platform. The sheave 68 is attached on the other side of the platform to the ends of the members 26 opposite the sheave 61. By this construction it will be noticed that the platform can be suspended 60 by its four corners, the cable 55 furnishing the support on one side, and the cable 65 on the other. By means of the motor 47, as described above, rotation can be given to the drums 41 and 42, to wind up the cables 65 and 55, respectively, and thus elevate the

platform. Suitable counterweights 81 are arranged at the end of the device, as shown, to assist in lifting.

Since the drum 41 is larger than the drum 42, the cable 65 will be taken up faster than the cable 55 in the elevating process, and this will give the platform and car thereon, as indicated by 82, a sideways tilt, as most clearly shown in Fig. 4. In the device, as shown, the drum 41 is enough larger so that 70 when the car is at the height of its elevation, which in this case is about seven feet, it will be given a sufficient sideways tilt to tend to cause the grain or contents thereof to flow towards the lower side of the car 80 and out of the side door. The tilt, however, is not sufficient to cause the car 82 to fall from the rails 21. It is obvious, however, that, without detracting from the spirit of my invention, the height of elevation of the 85 car and the amount of tilting may be varied, as desired, to suit existing conditions.

After the car has been raised to the extreme height and tilted sideways, it is rocked endwise in order to empty the grain or other material from the ends of the car. This endwise rocking is given while the sideways tilt is maintained, and is accomplished in the following manner. The drums 59 and 69 which each have wrapped 95 around them the cables 55 and 65, respectively, are mounted on a shaft 90 which carries a gear wheel 91 adapted to be driven by a worm 92 mounted on a shaft 93 which carries a belt wheel adapted to be driven by a belt 94 which in turn is adapted to be driven by the motor 47; any suitable clutching means, such as that indicated in general by 95, being provided to throw the motor 47 into or out of engagement with the belt 94. 100 By this construction rotation may be given to the drums 69 and 59 by the motor 47, and the worm 92 makes the action irreversible. It is obvious that the result of rotating the drums 69 and 59 will be to take up 110 the cables 55 and 65 where they pass over the sheaves 61 and 71 at one end of the platform, and play them out at the other end over the sheaves 58 and 68, thus lifting one end of the platform. Since the motor 115 47 is reversible, the drums 59 and 69 may be rotated either way to elevate either end of the platform. In Figs. 5 and 6 the platform is thus shown with one end elevated, the cables 55 and 65 having been taken up 120 where they pass over the sheaves 61 and 71 and paid out at the other end. This endwise tilting requires a pivoting of the sheaves 58, 68, 61 and 71 where they are attached to the ends of the members 26, and since 125 this endwise tilting is done while the sideways tilt is maintained, it is desirable that these pivot points at each end of the platform be brought in the same horizontal plane when the car is tilted sideways. For 130

this reason, the sheaves 58 and 61 on the low side of the platform are fastened to yokes 97 and 98, respectively, which have their ends fastened to blocks 99 and 100 which are fastened between the ends of the members 26. This brings the pivot points 101 and 102 slightly above the members 26 on the low side of the platform. On the other, or high, side of the platform, the sheaves 68 and 71 are fastened by two chain links 104 and 105 to an eye 106 fastened to a strip 107 arranged below the members 26. This construction is most clearly shown in Fig. 10, and brings the pivot point on the high side of the platform below the members 26 a sufficient distance so that when the platform has its maximum sideways tilt the pivot points 108 and 101 will be substantially in a horizontal plane.

Means are provided for preventing sideways swinging of the platform. I will now describe such means. At each end of the structure are rails 110 mounted on the inner surfaces of the posts 30. On each end of a bar 111 is a pair of vertical arms, one projecting upwardly as indicated by 113^a and the other downwardly as indicated by 113. Mounted on the ends of the arms 113^a and 113 are two rollers 112 and 114 respectively riding on the rail 110. The rollers 112 and 114 are suitably flanged in order to keep them on the rails. There being two rollers at each end of the bar 111, this bar will remain horizontal. The bar 111 carries at its center an eye 115 engaged with a yoke 116 attached to a carriage having horizontal rollers 117 and vertical rollers 118 riding on the lower outside webs of the I-beams 20. The rollers 117 and 118 permit endwise movement of the I-beams 20 with respect to the carriage but not sideways movement. Since sideways movement of the carriage is prevented by its connection with the bar 111, sideways movement of the entire platform is also prevented.

Box cars carrying grain and similar materials usually have, in addition to the ordinary sliding door, horizontally-arranged boards across the inside of the car-door opening, held in place by nails, by the pressure of the grain, or by other means. These boards are put in place to make it possible to close the car door after the car is loaded and to seal more effectively the car door against leakage of material. It is obvious that these boards must be removed before the car can be dumped. I have provided means for automatically removing these boards and I will now describe these means in detail.

It is to be noted that the ordinary sliding door on the outside of the car is opened before the car is run onto the platform or before the elevating or dumping is commenced. This leaves only the boards nailed across the inside of the opening to be removed be-

fore the contents can be dumped. For removing these boards I provide what might generally be described as a ram, adapted to be automatically operated by the elevation of the car, or by other means if desired, to 70 forcibly push the boards inwardly against the pressure of the grain and thus remove them from the car-door opening to allow the grain to escape. The particular device which I have shown comprises a ram 200 75 pivotally mounted at 201 on the supporting members 202 which in turn are supported by the beams 203 mounted on the elevator platform. The back of the ram is curved in the form of an arc about the pivot point 201 as 80 a center, as indicated by 205. Fastened to one end of the arc at 206 is a cable 207 which is laid in a groove about the arc 205 thence led downwardly under a pulley 208 mounted on the elevator platform, thence toward the 85 center of the platform and over a pulley 209 suspended below the platform and thence downwardly and attached at 210 at the bottom of the pit below the platform. The cable 207 is of sufficient length so that when 90 the elevator platform is down, the ram 200 will be in the position shown in Fig. 3 with its engaging face hanging downwardly. The counterweight 500 fastened on the cable 501 passing over the sheave 502 causes the 95 ram to take this position when the elevator platform is down; the lower end of the cable 501 being attached to the arc 205 at a point as indicated by 503, and adapted to lie in a groove on said arc lying parallel to 100 the groove which accommodates the cable 207. When the elevator platform is raised, the consequent pull on the cable 207, will rock the ram, causing its engaging face, indicated in general by 212, to be forced inwardly, through the car-door opening against the boards nailed across such opening, with the result that such boards will be forcibly pushed loose from their fastenings and against the pressure of the grain 110 into the car to open the car-door opening. The ram is so located that when the car is properly in position on the elevator platform, the engaging face of the ram, as it is swung by the cable 207, will enter the car-door opening. In Fig. 4 the ram is shown in the position it occupies after the car has been elevated and after it has been rocked to force the face 212 through the car-door opening to remove the boards 115 which are indicated by 220. The engaging face 212 of the ram is provided with a vertically slidable engaging block 212^a which is provided on its engaging surface with spikes or prongs 213 adapted to engage the boards 120 220. This construction is most clearly shown in Figs. 7, 8 and 9. The engaging block 212^a is normally held in its raised position by the lever 214 and weight 215 as shown in Fig. 7. Since the ram 200 is op- 130

erated by rotation at 201 the face 212 has a slight upward movement with respect to the car as it approaches the boards 220. The engaging block 212^a is provided to counteract this upward movement so that as the prongs 213 engage the boards 220 there will be no upward sliding of the prongs on the boards with consequent damage to the boards. As soon as the prongs 213 engage the boards 220, the engaging block 212^a is prevented from moving upwardly, with the result that the face 212 of the ram slides upwardly thereon; such upward sliding being permitted by elevation of the weight 215 and downward pulling of the end of the lever 214 which is hooked to the upper end of the block 212^a. This sliding of the block 212^a with respect to the face 212 prevents sliding of the prongs 213 on the boards 220. It is obvious, however, that during such sliding, the rotation of the ram continues to give the engaging block 212^a inward pressure against the boards on the car-door opening to remove them from their fastenings and force them inwardly from the car-door opening to allow the grain to escape. In Fig. 8 the block 212^a is shown engaged with the boards 220, the face 212 of the ram being slipped upwardly over the back of the block 212^a until it has engaged the stop 600 on the block 212^a, after which both the face 212 and the block 212^a act as one piece. After the boards have been removed the weight 215 operates automatically to again raise the block 212^a for the next operation.

Any suitable means are provided for spotting, centering or holding the car 82 on the platform during the dumping operation. I have indicated such means in general by 300, which are stops at the ends of the platform, adapted, in any suitable manner, to be lowered out of position when the car 82 is run onto or off of the platform, and to be put into raised position, as shown in the drawings, to bear firmly against the ends of the car, as shown, to hold it in proper position during the elevating, tilting and dumping. I have not shown the details of construction of such stops, since they may be made by any skilled mechanic in a great variety of forms.

At one side of the car, at the center, opposite the door, is a pit 400 having located within it a hopper, or bin, 401 with side walls 402, adapted to receive the grain dumped from the car. A suitable grating 403 is arranged above the hopper. The grating 403 is depressed at the center to accommodate the door-opening ram 200.

In the operation of the device, the car 82 is run onto the elevator, the stops 300 are put in place, and the car is then lifted. This lifting operates the ram to remove the boards from the car-door opening, and also 65 tilts the car sideways, with the result that

the grain from the center of the car runs out of the car-door opening through the grating 403 into the hopper 401. This sideways tilting, however, will not empty the ends of the car. The drums 59 and 69 are then operated to lift first one end of the car and then the other until the car is entirely emptied.

Although I have shown the elevating of the car as giving it a sideways tilt, in regard to certain phases of my invention, such sideways tilting is not absolutely necessary. For example, the car could be raised, maintaining it level, and then could be dumped by the endwise rocking alone, by using baffle plates or boards arranged across the center of the car to direct the grain out of the door as it slides down from the elevated end.

It is obvious that although I have shown a device which elevates a car about seven feet, such elevation may be more or less, as desired, without detracting from the spirit of my invention. For example, the elevation could be of such a height that the hopper 401 could be raised entirely above the ground level, and the excavation entirely done away with. Also, if desired, the excavations under the platform could be deeper, so that the car would not be elevated as high as shown. The bodily elevation of the car, so far as regards certain phases of my invention, could be entirely dispensed with, and the car merely rocked sideways and then endwise in order to empty the contents.

Therefore, while I have shown and described but a single embodiment of my invention, it is to be understood that it is capable of many modifications. Changes, therefore, as suggested above, in the height of elevation, the sideways tilting, the arrangement of the excavations and hoppers, and other changes in the construction and arrangement of the various parts, and the operation of the same, may be made without departing from the spirit and scope of my invention as disclosed in the appended claims, in which it is my intention to claim all the novelty inherent in my invention as broadly as is possible in view of the prior art.

What I claim as new, and desire to secure by Letters Patent, is:

1. A car dumper comprising a platform adapted to receive a car to be dumped, means for elevating the platform bodily, means for tilting the same sidewise, and means for tilting the same in a vertical longitudinal plane.

2. A car dumper comprising a platform adapted to receive a car to be dumped, means for simultaneously elevating the platform and tilting the same sidewise, and means for tilting the same in a vertical longitudinal plane.

3. A car dumper comprising a platform

adapted to receive a car to be dumped, means for elevating the platform, means for tilting the same sidewise, and means for tilting the same in a vertical longitudinal plane while maintaining the sidewise tilt.

4. A car dumper comprising a platform adapted to receive a car to be dumped, means for elevating the platform bodily, means for tilting the same sidewise, and means for rocking the same in a vertical longitudinal plane.

5. A car dumper comprising a platform adapted to receive a car to be dumped, means for simultaneously elevating the platform and tilting the same sidewise, and means for rocking the same in a vertical longitudinal plane.

6. A car dumper comprising a platform adapted to receive a car to be dumped, means for elevating the platform, means for tilting the same sidewise, and means for rocking the same in a vertical longitudinal plane while maintaining the sidewise tilt.

25 7. A car dumper comprising a platform adapted to receive a car to be dumped, said platform suspended at each end from a sheave in the bight of a cable, one lead of cable from each of said bights being joined together, and means for moving said cable to simultaneously pay out one of said bights and take up the other to tilt the platform in a vertical longitudinal plane.

35 8. A car dumper comprising a platform adapted to receive a car to be dumped, sheaves on each side of said platform for suspending the same, cables in the bights of which said sheaves are suspended, and overhead sheaves about which said cables are reeved, whereby power applied to said cables will elevate one end of said platform and correspondingly lower the other end.

9. A car dumper comprising a platform adapted to receive a car to be dumped, 45 said platform suspended at its corners from four sheaves, each of the sheaves being supported in the bight of a cable, the two sheaves on each side being joined by a single cable, and means for moving the cables to simultaneously pay out the bights at one end of the platform and take up those at the other to tilt the platform in a vertical longitudinal plane.

55 10. A car dumper comprising a platform adapted to receive a car to be dumped, a cable for suspending said platform at its ends, means for moving said cable, said cable and its actuating means being so disposed relative to each other that movement 60 of the cable to lower one end of the platform will operate to correspondingly elevate the other end of the platform.

11. A car dumper comprising a platform adapted to receive a car to be dumped, 65 a plurality of cables for supporting said

platform at its ends, means for moving said cables, said cables and their actuating means being so disposed relative to each other that movements of the cables to lower one end of the platform will correspondingly elevate the other end of the platform in a vertical longitudinal plane.

70 12. A car dumper comprising a platform adapted to receive a car to be dumped, cables suspending said platform at its corners, means for moving said cables, means interposed between said actuating means and the platform with which the cables contact, whereby to cause a movement of the cables to lower one end of the platform to correspondingly elevate the other end of the platform.

75 13. A car dumper comprising a platform adapted to receive a car to be dumped, said platform suspended at its corners from sheaves, each of said sheaves being so supported in the bight of a cable as to cause movement of the cables to pay out the bights at one end of the platform to operate to correspondingly take up the bights at the other end of said platform.

80 14. A car dumper comprising a platform adapted to receive a car to be dumped, said platform suspended at each end from a sheave, each of said sheaves being so supported in the bight of a cable as to cause movement of the cable to pay out the bight at one end of the platform to operate to correspondingly take up the bight at the other end of said platform.

85 100 15. A car dumper comprising a platform adapted to receive a car to be dumped, said platform suspended at each end from a sheave in the bight of a cable, one lead of cable from each of said bights being joined together, means for simultaneously elevating the platform and tilting the same sidewise, and means for moving said cable to simultaneously pay out one of said bights and take up the other to tilt the platform in a vertical longitudinal plane.

95 105 110 115 120 16. A car dumper comprising a platform adapted to receive a car to be dumped, means for simultaneously elevating the platform and tilting the same sidewise comprising sheaves on each side of said platform and suspending the same, cables in the bights of which said sheaves are suspended, overhead sheaves about which said cables are reeved, and power means adapted to actuate said sheaves and cables to elevate one end of the platform and correspondingly lower the other end.

125 17. A car dumper comprising a platform adapted to receive a car to be dumped, means for simultaneously elevating the platform and tilting the same sidewise, said platform suspended at its corners from four sheaves, each of the sheaves being supported in the bight of a cable, the two sheaves on each

side being joined by a single cable, and means for moving the cables to simultaneously pay out the bights at one end of the platform and take up those at the other 5 to tilt the platform in a vertical longitudinal plane.

18. A car dumper comprising a platform adapted to receive a car to be dumped, means for simultaneously elevating the platform and tilting the same sidewise, a cable suspending said platform at its ends, and means traversed by the cable to cause movement thereof to lower one end of the platform to correspondingly elevate the other 15 end of said platform.

19. A car dumper comprising a platform adapted to receive a car to be dumped, means for simultaneously elevating the platform and tilting the same sidewise, cables suspending said platform at its ends and means traversed by the cables to cause movement thereof to lower one end of the platform to correspondingly elevate the other 20 end of said platform.

25 20. A car dumper comprising a platform adapted to receive a car to be dumped, means for simultaneously elevating the platform and tilting the same sidewise, cables suspending said platform at its corners and 30 means traversed by the cables to cause movement thereof to lower one end of the platform to correspondingly elevate the other end of said platform.

21. A car dumper comprising a platform 35 adapted to receive a car to be dumped, means for simultaneously elevating the platform and tilting the same sidewise, sheaves suspending the said platform at its corners, a cable in the bight of which each of said 40 sheaves is supported, whereby movement of the cables to pay out the bights at one end of the platform will operate to correspondingly take up the bights at the other end of said platform.

45 22. A car dumper comprising a platform adapted to receive a car to be dumped, means for simultaneously elevating the platform and tilting the same sidewise, a sheave suspending each end of said platform, a cable 50 in the bight of which said sheave is supported, whereby movement of the cable to pay out the bight at one end of the platform will operate to correspondingly take up the bight at the other end of said platform.

55 23. A car dumper comprising a platform adapted to receive a car to be dumped, said platform suspended at each end from a sheave in the bight of a cable, one lead of cable from each of said bights being joined 60 together, means for elevating the platform, a ram operated by elevation of the platform adapted to be forced through the car-door opening of a car on the platform, and means for moving said cable to simultaneously pay 65 out one of said bights and take up the other

to tilt the platform in a vertical longitudinal plane.

24. A car dumper comprising a platform adapted to receive a car to be dumped, means for elevating the platform, a ram 70 operated by elevation of the platform adapted to be forced through the car-door opening of a car on the platform, sheaves suspending the sides of said platform, a cable forming a bight in which said sheaves are suspended, 75 a system of sheaves overhead over which said cables are reeved, and means for applying power to said sheaves to cause the cables to elevate one end of the platform and correspondingly lower the other end. 80

25. A car dumper comprising a platform adapted to receive a car to be dumped, means for elevating the platform, a ram operated by elevation of the platform adapted to be forced through the car-door opening of a 85 car on the platform, said platform suspended at its corners from four sheaves, each of the sheaves being supported in the bight of a cable, the two sheaves on each side being joined by a single cable, and means for moving the cables to simultaneously pay out the bights at one end of the platform and take up those at the other to tilt the platform in a vertical longitudinal plane. 90

26. A car dumper comprising a platform 95 adapted to receive a car to be dumped, means for elevating the platform, a ram operated by elevation of the platform adapted to be forced through the car-door opening of a car on the platform, said platform suspended at 100 its ends by a cable, and means for movement of said cable so disposed relative thereto that movement of the cable to lower one end of the platform will operate to correspondingly elevate the other end of said platform. 105

27. A car dumper comprising a platform adapted to receive a car to be dumped, means for elevating the platform, a ram operated by elevation of the platform adapted to be forced through the car-door opening of a 110 car on the platform, a plurality of cables suspending said platform at its ends, and means for operating said cables whereby movement of the cables to lower one end of the platform will operate to correspondingly 115 elevate the other end of said platform.

28. A car dumper comprising a platform adapted to receive a car to be dumped, means for elevating the platform, a ram operated by elevation of the platform adapted to be 120 forced through the car-door opening of a car on the platform, cables suspending said platform at its corners, and means for operating said cables whereby movement of the cables to lower one end of the platform will operate to correspondingly elevate the other end of said platform. 125

29. A car dumper comprising a platform adapted to receive a car to be dumped, means for elevating the platform, a ram operated 130

- by elevation of the platform adapted to be forced through the car-door opening of a car on the platform, sheaves suspending said platform at its corners, a cable in the bight 5 of which said sheaves are suspended whereby movement of the cables to pay out the bights at one end of the platform will operate to correspondingly take up the bights at the other end of said platform.
- 10 30. A car dumper comprising a platform adapted to receive a car to be dumped, means for elevating the platform, a ram operated by elevation of the platform adapted to be forced through the car-door opening of a car 15 on the platform, a sheave, suspending each end of said platform in the bight of a cable in the bight of which each of said sheaves is supported, means for operating said cables whereby movement of a cable to pay out the bight at one end of the platform will operate to correspondingly take up the bight at the other end of said platform.
- 20 31. A car dumper comprising a platform adapted to contain a car to be dumped, means for elevating the platform, and a ram arranged at the side of the platform and adapted by elevation of the platform to be forced through the car-door opening of a car standing on the platform.
- 25 32. A car dumper comprising a platform adapted to contain a car to be dumped, means for elevating the platform bodily, means for tilting the same sidewise, and means for tilting the same endwise.

In testimony whereof I have hereunto set 35 my hand and seal this 28 day of June 1921.

LIONEL COKE HILL. [L. s.]
